Primary Examiner — Clare Ann Gannon

(57) **CLAIM**

The ornamental design for doormat as shown and described.

DESCRIPTION

The patent or application file contains at least one drawing executed in color. Copies of this patent or patent application publication with color drawing(s) will be provided by the Office upon request and payment of the necessary fee.

1. Doormat
2. Doormat
3. Doormat
4. Doormat
  - 1.1 is a bottom plan view
  - 1.2 is a top perspective view
  - 1.3 is a top perspective view
  - 1.4 is a top perspective view
  - 1.5 is a top plan view
  - 2.1 is a top plan view
  - 2.2 is a top perspective view
  - 2.3 is a top perspective view
  - 2.4 is a bottom plan view
  - 2.5 is a front perspective view
  - 3.1 is a top plan view
  - 3.2 is a top perspective view
  - 3.3 is a front perspective view
  - 3.4 is a bottom plan view
  - 3.5 is a top perspective view
  - 4.1 is a top perspective view
  - 4.2 is a front perspective view
  - 4.3 is a top perspective view
  - 4.4 is a bottom plan view

For designs 1-3: The characteristic features of the design lie in the combination of the color and shape; For design 4: the characteristic features of the design lie in the shape.
